CHAIR

Clyde E. Yost, Grand Rapids, Mich., assignor to
American Seating Company, Grand Rapids,
Mich., a corporation of New Jersey

Application October 31, 1938, Serial No. 237,806

3 Claims. (Cl. 155—130)

The present invention relates to chairs, particularly such as are installed in auditoriums, stadia, and the like; and its object is, generally, to provide an improved chair structure including chaplets whereby the back of the chair is mounted on its supporting standards; and particularly, to provide such a structure and chaplets whereby the curvature of a row of chairs and the spacing thereof may to a considerable degree be adjusted to meet the requirements of particular installations; and further, to provide in such a structure chaplets partially embedded in, and thus firmly held by, the chair's cast metal standards in the molding thereof; and further, to provide an improved method for thus forming such standards and chaplets.

These and any other objects hereinafter appearing are attained by the method and the illustrative structure particularly described in the body of this specification, said structure which constitutes a preferable physical embodiment of the invention being illustrated by the accompanying drawings, in which—

Figure 1 is an elevational rear view of a portion of a standard common to a pair of chairs and portions of the backs of said chairs mounted on the standard by the chaplets;

Figure 2 is a horizontal sectional view thereof taken on line 2—2 of Figure 1;

Figure 3 is a vertical sectional view of the same taken on line 3—3 of Figure 2;

Figure 4 is a perspective view of one of said chaplets;

Figure 5 is a front side view thereof;

Figure 6 is a plan view of the same;

Figure 7 is an outer end view thereof;

Figure 8 is a horizontal sectional view of the same taken on line 8—8 of Figure 5;

Figures 9, 10, 11, 12, 13 and 14 illustrate means and indicate the method for molding the chair's metal standard to partially embed and firmly hold the chaplets therein. In these views, Figure 9 is a sectional view of the molding pattern for the standard taken on line 9—9 of Figure 11;

Figure 10 is a sectional view of the pattern taken on line 10—10 of Figure 12, and a rear view of a chaplet positioned thereon;

Figure 11 is a sectional view of the pattern taken on line 11—11 of Figure 9;

Figure 12 is a sectional view of the pattern and chaplet thereon taken on line 12—12 of Figure 10;

Figure 13 is a perspective view of the pattern and the chaplet moved toward its proper position thereon;

Figure 14 is a sectional view of the molded standard with the chaplet in the sand of the mold, taken on a plane corresponding with that on which Figure 12 is shown sectioned;

Figure 15 shows a modified construction of the chaplet; and

Figure 16 is a sectional view thereof on line 16—16 of Figure 15.

As illustrated by these drawings, the backs 1 of a pair of chairs are mounted on an intervening standard 2 having at its rear side a boss 20 with integral opposite horizontally extending wings 3 wedge shaped in horizontal section, the front sides 24 of the wings being inclined laterally-rearwardly, as best seen in Figure 2, and the wings having medial depressions whose bottoms 35 are parallel with said front sides.

A chaplet 4 on each of the wings is desirably made of sheet metal bent to form at the chaplet's outer end a bight portion 5, a forward leaf 6 and a rearward leaf 7 which has vertically spaced, rearwardly extending and triangularly shaped portions 8 with upwardly and downwardly extending flanges 9 respectively. These leaves 6, 7 parallelly spaced apart have registering horizontally elongated slots 10 therethrough with surrounding inwardly turned flanges 11 whose edges mutually contact. The chaplet is held in a closed horizontal slot 12 of the standard's wing 3 which registers with the slots 10 of the chaplet's forward and rearward leaves 6, 7, the horizontal edge portions 26 of the chaplet's forward leaf seating in a pair of rabbet grooves 14 in the front side 24 of the wing 3, the flanges 9 of its rearward leaf seating in a pair of rabbet grooves 15 in the wing's rear side 25 and the standard, when of cast metal molded as hereinafter described, extending around the chaplet's flanges 11.

A bolt 16 extending through the chaplet's slots 10, the standard's slot 12 and an opening 17 in the chair back secures the same in place, having a nut 18 which with the washer 19 contacts the rear side of the rearward leaf 7 which rests on the bottom 35 of said medial depression in the wing.

As illustrated, the standard desirably has opposite strengthening ribs 21 at its forward side and similar ribs 22 extending above and below the boss 20 at its rearward side.

The standard is desirably made of metal cast to partially embed and securely hold chaplets therein. For thus casting the standard, a suitable pattern 23 therefor, shown in Figures 9—13, is prepared whose parts, corresponding respectively with the parts of the molded standard 2,

are indicated on these views by the same reference numerals, with prime marks added.

The chaplets 4 are applied to the pattern's parts 3¹ (which correspond with the standard's wings 3) so as to occupy the same relative positions that the chaplets and the standard's wings occupy. To thus apply the chaplets to the pattern, each chaplet is slid into the open-end slot 12¹ of the pattern's part 3¹ as indicated in Figure 13, the chaplet's flanges 9 sliding in said part's rabbet grooves 15¹, and when the chaplet reaches its innermost position, the vertical inner edges 27, 28 of its parallel forward and rearward leaves contact at 29, 30 respectively the inner end 36 of slot 12¹ as best seen in Figure 12, thus closing off the space between the chaplet's leaves and around their meeting flanges 11, the horizontal edge portions 26 of the forward leaf and the flanges 9 of the rearward leaf closely seating in the rabbet grooves 14¹ and 15¹ of the forward and rearward sides 24¹ and 25¹ respectively of the pattern's part 3¹. Said pattern with the chaplets thus applied thereto is used for molding the standard with the chaplets partially embedded therein, by usual foundry methods.

The sand 32, 33 of a two-part mold is packed on the opposite sides of the pattern and around the chaplets thereon respectively so as to pass through the semicircular bottom 34 of the slot 12 and into the chaplets' slots 10. Whereupon, the mold's parts being separated and the pattern 23 withdrawn, the chaplets remain in the sand, so that when the mold's parts are assembled and the molten metal poured thereinto, the metal fills the space between the chaplets' leaves 6, 7 and around the flanges 11.

In its modified construction illustrated by Figures 15 and 16, the chaplet 4¹ has the bight outer end portion 5¹ and spaced leaves 6¹, 7¹ with medial slots 10¹ therethrough which have closed inner ends 35 and inwardly turned flanges 11¹.

The chaplet is firmly held in the cast metal body 2² by being fused therewith in the casting of said body with the chaplet partially embedded therein.

The invention being intended to be pointed out

in the claims, is not to be limited to or by details of construction of the physical embodiment thereof illustrated by the drawings, or of the method hereinbefore described.

5 I claim:

1. In a chair: a back; a standard having a lateral wing, the front side of the wing being inclined laterally-rearwardly and the rear side of the wing having a medial depression; a chaplet having forward and rearward leaves engaging the wing's front side and the bottom of the depression respectively, the leaves and the wing having horizontally elongated registering slots; means extending through the slots of the leaves and the wing for adjustably mounting the back on the standard.

10 2. In a chair: a back; a standard having a lateral wing with an opening therethrough and front and rear inwardly diverging sides, one of said sides having a medial depression with its bottom parallel with the wing's other side; a chaplet in the opening having spaced leaves engaging one side of the wing and the bottom of the depression respectively, the wing and the leaves having registering openings therethrough; means extending through the openings of the leaves and the wing for mounting the back on the standard.

15 3. In a chair: a back; a standard having a lateral wing with an opening therethrough and front and rear inwardly diverging sides, one of said sides having a medial depression with its bottom parallel with the wing's other side and having grooves parallel with the opening; a chaplet in the opening having spaced leaves engaging one side of the wing and the bottom of the depression in the wing's other side respectively, the leaves having openings therethrough registering with the wing's opening, one of the leaves having upper and lower portions with oppositely turned flanges engaging in the grooves respectively; means extending through the openings of the leaves and the wing for mounting the back on the standard.

CLYDE E. YOST.
